UNITED STATES PATENT OFFICE.

ALFRED LEE, OF AKRON, OHIO.

DESIGN FOR FLOOR OR WALL COVERING.

No. 38,406.

Specification for Design.

Patented Jan. 8, 1907.

Application filed November 23, 1906. Serial No. 344,789. Term of patent 14 years.

To all whom it may concern:

Be it known that I, ALFRED LEE, a citizen of the United States, residing at Akron, in the county of Summit and State of Ohio, have invented a new, original, and ornamental Design for Floor or Wall Covering, of which the following is a specification, reference being had to the accompanying drawing, forming a part hereof.

I claim—

The ornamental design for floor or wall covering, as shown.

ALFRED LEE.

In presence of—

C. E. HUMPHREY,
GLENARA FOX.
